CLAIM

The ornamental design for a joystick game controller, as shown and described.

DESCRIPTION

FIG. 1 is a front elevation view of the joystick game controller;

FIG. 2 is a rear elevation view of the joystick game controller;

FIG. 3 is a left side elevation view of the joystick game controller;

FIG. 4 is a right side elevation view of the joystick game controller;

FIG. 5 is a top plan view of the joystick game controller; and,

FIG. 6 is a bottom plan view of the joystick game controller. The broken lines shown in the drawings are for the purpose of illustrating portions of the joystick game controller that form no part of the claimed design.
